ABSTRACT

A dentifrice suitable for removing calculus and preventing the build-up of calculus on tooth enamel which contains strontium edetate and a ricinoleate, which have been found to provide a synergistic effect in both removal of calculus and prevention of its build-up.

DENTIFRICE

Matter enclosed in heavy brackets [ ] appears in the original patent but forms no part of this reissue specification; matter printed in italics indicates the additions made by reissue.

This invention relates to dental hygiene and, in particular, provides a dentifrice having valuable properties in the removal and prevention of calculus.

BACKGROUND OF THE INVENTION

It is known that water-containing dentifrices which include strontium and sequestering agents such as 15 EDTA are effective in the treatment of hyper-sensitive dentin, gingivitis and periodontitis, apparently through the mechanism of substituting strontium for calcium in the calcium hydroxy apatite of the tooth (Schole et al. U.S. Pat. No. 3,699,221 and 3,988,434).

It is also known that ricinoleic acid and various esters and salts which are surface active agents exhibit a higher contact angle with tooth enamel than other surface active agents.

SUMMARY OF THE INVENTION

In accordance with the present invention, a water-containing dentifrice including both strontium edataate and a ricinoleate provide a synergistic action in the removal of calculus from teeth and also in the prevention of its build-up.

It is understood by strontium edataate reference is made to the strontium chelate of EDTA and preferably the disodium strontium salt of ethylene diamine tetraacetic acid. When strontium edataate is present in an 35 aqueous composition, the strontium is available in ionic form. Generally, the amount of strontium present in the dentifrice can be up to about 25 wt. % of strontium [ion] edataate in the toothpaste, but much smaller amounts, as low as 2.5 wt. %, are effective. The strontium edataate can be formed in advance or can be prepared in the dentifrice as a mixture of a water soluble salt of EDTA together with a pharmacalogically innocuous water-soluble strontium salt, preferably in equivalents such that the pH will remain neutral.

The ricinoleate can be any of the alkali metal salts of ricinoleic acid (d-12-hydroxy-cis-9-octadecenoic acid), but preferably is the sodium salt. The amount of the ricinoleate is not particularly critical and can be as high as 10 wt. %. Amounts as low as 0.1 wt. % are, however, 50 also effective.

The preferred proportions in the water-containing dentifrice are 10% by weight of strontium, calculated as disodium strontium ethylene diamine tetra acetate and 55 0.5% by weight of ricinoleate, calculated as the sodium salt.

The dentifrice product used should not include any calcium or other metal, salt or compound, from which any such metal would be sequestered by, and form the corresponding calcium or other metal chelate with the 60 EDTA salt or chelate residue of the strontium chelate in the product.

In other words, the dentifrice products of the invention should not include any of the water-insoluble calcium, magnesium or aluminum compounds ordinarily 65 incorporated as adjuvant bulk excipients in dentifrices, for example, as the abrasive ingredient, such as calcium carbonate, calcium pyrophosphate, magnesium oxide,

aluminum oxide or hydroxide, and the like. So also, tin compounds, e.g., stannous fluoride and stannous chlorofluoride, likewise should be excluded.

In place of the foregoing water-insoluble bulk excipients for abrasive and other purposes, water-insoluble barium and strontium salts, for example, barium sulphate, barium carbonate, strontium carbonate and strontium phosphate can be used. The ricinoleate, being a surface-active wetting agent which is compatible with strontium, generally will obviate the need of other wetting agents.

The following are examples of several dentrifrices in accordance with the invention.

EXAMPLE 1—TOOTHPASTE

Disodium Salt	20	grams
of Ethylenediamine Tetraacetic Acid	20	grams
Strontium Chloride (6H ₂ O)	20	grams
Strontium Carbonate	25	grams
Sodium Ricinoleate	0.5	grams
Algin	1	gram
Essential Oils (for flavoring)	1	gram
Propylene Glycol	25	grams
Alcohol	0.9	gram
Water quantity sufficient to make	100	grams

EXAMPLE 2—TOOTHPASTE

Strontium Edataate	30	grams
Barium Sulfate	30	grams
Sodium Ricinoleate	1.0	gram
Algin	1	gram
Essential Oils (for flavoring)	1	gram
Propylene Glycol	20	grams
Alcohol	0.9	gram
Water quantity sufficient to make	100	grams

EXAMPLE 3—TOOTHPASTE

Strontium Edataate	8.0	grams
Strontium Carbonate	25.0	grams
Methyl Salicylate	1.25	grams
Water	33	cc
Natrosol	1.7	grams
Sodium Ricinoleate	.1	gram
Cpc	.3	gram
Sodium Saccharin	1.2	grams
Propylene glycol	25	cc
Water sufficient to make	100	grams

EXAMPLE 4-6—TOOTHPASTE

	Preparation		
	4	5	6
Strontium Edataate	30	20	10
Strontium Carbonate	25.0	25.0	25.0
Cetyl pyridinium chloride	0.5	0.5	0.5
Oil of cassia	0.75	0.75	0.75
Oil of wintergreen	1.0	1.0	1.0
Propylene glycol	25.0	25.0	25.0
Natrosol	1.7	1.7	1.7
Saccharin	1.2	1.2	1.2
Sodium Ricinoleate	1.5	.5	.1
Water QSAD to 100 grams			

Strontium edataate is prepared by mixing equimolar amounts of strontium chloride hexahydrate and disodium ethylene diamine tetraacetic acid in hot distilled

water, typically at 70° C., for a period of 20 minutes. The weight of strontium edetate is calculated as disodium strontium ethylene diamine tetraacetate and does not include the chloride present. As the ligand is formed, the two hydrogen ions are released for each molecule of Na₂ EDTA which results in a decrease of solution pH from about neutral to about 4, indicating the formation of the ligand. Strontium carbonate or 10 other abrasive then is slowly added to the mixture and heating and mixing are continued as the strontium carbonate or other abrasive is mixed. When strontium carbonate is used, a reaction takes place with a visible 15 evolution of carbon dioxide as the vapor. This reaction continues for about three to four hours at 70° C. The mixture is allowed to cool and additional ingredients such as propylene glycol and the like are added as well 20 as make up water for that lost during the mixing of the strontium carbonate, Na₂ EDTA and strontium chloride. In Example 1, an excess of strontium chloride was utilized and hence this is separately stated. In Example 25 2, barium sulfate was substituted for strontium carbonate.

In a preferred alternate method of manufacture, Strontium edetate can be made by adding Strontium 30 Carbonate to an aqueous solution of Disodium EDTA at a temperature 70° C.-80° C. The Strontium Carbonate is added slowly. At the completion of the reaction the pH will be between 7 and 8 which is adjusted by 35 adding HCl. The bulk excipient or abrasive, such as Insoluble Metaphosphate (IMP) or Strontium Carbonate is added. The mixture is completed with the addition of Thickening Agent (Natrosol), Humectant (Sorbitol 40 and Glycerine), Surfactant (Sodium Ricinoleate) and flavoring.

EXAMPLE 7

Liquid Dentifrice		
Sodium Ricinoleate	0.5	gram
Glycerine	20	grams
Oil of cloves	0.3	gram
Oil of spearmint	0.3	gram
Oil of cassia	0.3	gram
Saccharin	0.5	gram
Strontium edetate	10	grams
Tincture cudbear	0.6	gram
Water quantity sufficient to make	100	cc

The alcohol and glycerine are added to one another and stirred together, and, the ricinoleate then is dissolved in the alcohol and glycerine solution. The saccharin then is stirred in and also the tincture cudbear for coloring. Then the strontium edetate (crystalline) is stirred in and followed by the flavoring ingredients, namely, the oils of cloves, spearmint, and cassia; and finally the water is added, and the whole is stirred to uniformity.

The toothpastes of Examples 1-6 are utilized following a regular daily routine preferably twice a day. The liquid dentifrice of Example 7 is preferably used as a mouthwash and can be diluted in water, as with any ordinary mouthwash, and preferably is used at least twice a day.

I claim:

1. A water-containing dentifrice consisting essentially of strontium edetate in an amount sufficient to provide from about 2.5 wt. % to about 25 wt. % of strontium [ion] edetate and from about 0.1 wt. % to about 10 wt. % of a ricinoleate compound said dentifrice being free from strontium edetate-sequestering Ca, Mg, Al, Sn metal.
2. A dentifrice according to claim 1 in which the ricinoleate is sodium ricinoleate.
3. A method for controlling calculus which comprises applying to the teeth a water-containing dentifrice consisting essentially of strontium edetate in an amount sufficient to provide from about 2.5 wt. % to about 25 wt. % of strontium [ion] edetate and about 0.1 wt. % to about 10 wt. % of a ricinoleate said dentifrice being free from strontium edetate-sequestering Ca, Mg, Al, Sn metal.
